UNITED STATES PATENT OFFICE.

LEONED M. KUNISIN, OF CHICAGO, ILLINOIS.

PNEUMATIC SIGNAL.

1,331,158.

Specification of Letters Patent. Patented Feb. 17, 1920.

Application filed February 4, 1918. Serial No. 215,335.

To all whom it may concern:

Be it known that I, LEONED M. KUNISIN, a citizen of the United States, residing at Chicago, in the county of Cook and State 5 of Illinois, have invented certain new and useful Improvements in Pneumatic Signals, of which the following is a specification.

This invention relates to automobile signals, and has particular reference to direction signaling mechanisms.

The object of the invention is to provide a pneumatically operated direction signal by means of which a right-hand or a left-hand indicating arm may be thrown into 15 operative position.

A still further object of the invention is to provide a unique form of signaling arm and operating device therefor, which while operating quickly and positively will, at the 20 same time withstand the wear and tear of usage.

With the above and other objects in view, and such others relating to the details of construction as may hereinafter appear, my 25 invention will now be fully set forth and described reference being had to the accompanying drawings, in which like reference characters indicate like parts throughout, and:

30 Fig. 1 is a part elevational and a part diagrammatic view showing fragments of the car and the engine casing so that a comprehensive idea of the invention may be gathered.

35 Fig. 2 is a view part elevational and part sectional, of one of the signaling devices.

Fig. 3 is a side elevation thereof.

40 Fig. 4 is a section on the line 4—4 of Fig. 3.

Fig. 5 is a section on the line 5—5 of Fig. 1.

Fig. 6 is a section on the line 6—6 of Fig. 2.

45 Fig. 7 is a fragmentary elevational view showing a signal arm in operative position, and

50 Figs. 8 and 9 are an elevation and a side view, respectively, showing a cover or casing which is employed to protect the mechanism of the signal devices.

Referring more particularly to the drawings 55 1 represents the frame of the lower section of a wind-shield which is mounted in the usual manner upon an automobile. Clamped to the vertical end pieces of the

frame 1 are the base plates 2, the base plates 2 having the lower widened portions 3 to the rear faces of which the clamps 4 are secured. Said clamps 4 each consist of a 60 body and a hinged plate 5 which are shaped to surround the frame pieces, suitable packing elements 6 being interposed between the clamp members and the frame, as best indicated in Fig. 5.

65 Mounted upon each of the extension sections 3 of the base plates 2 is a vertically disposed cylinder 7 within which the piston 8 operates. A stem 9 rising from a piston head 8 and extending through the movable 70 top 10 of the cylinder is provided with a rearwardly turned horizontal member 11 which operates in a guide block 12 which receives from the base plate 2, the guide block 12 being vertically grooved to operatively receive the extension 11 as the piston is reciprocated in its cylinder. Mounted upon the extension 11 is a link 13 so that it may swing transversely therein, said link 13 having its opposite end pivotally connected to a crank disk 14 which is rotatably mounted upon the face of the base plate 2. Extending upwardly from the crank disk 14 is a comparatively long arm 15 which constitutes a semaphore arm and carries at its 80 free end the target 16. When the piston 8 is forced upwardly in the cylinder 7, the crank disk 14 is operated to throw the arm 15 into horizontal position, the connection of the link 13 to the crank disk being to 90 one side of the dead center line so that the arm 15 will be operated in the proper direction. The limit of movement into horizontal position of the arm 15 is determined by a tubular extension 17 which surrounds 95 the stem 9 within the cylinder 7 and acts as a stop against which the piston 8 strikes when it is forced upwardly. Bleed openings 18 formed in the cap 10 permit the free progress of the piston 8 within its cylinder. 100 When the piston 8 is forced upwardly, it operates against the tension of a pair of contractile springs 19 which are connected between a cross head 20 on the stem 9 and the cap 10. When the arm 15 is drawn into vertical position by the action of the springs 19 it strikes against a spring stop 21 which determines its vertical or neutral position.

105 The track 16 has a circular casing having front and rear transparent covers 22 which 110 may have indicated thereon the direction arrows 23. Mounted across the interior of

the casing of the target 16 is a web 24 within which a signal light 25 is socketed. The lamp 25 is wired into a suitable electric circuit, the conductors being extended through 5 a tubular passage 26 which is formed through the arm 15 and within the crank disk 14 communicates with a contact member 27. A second contact member 28 extends across the path of movement of the 10 contact 27, so that when the arm 15 is swung into position, the contact members 27 and 28 connect to join the conductor into the electric circuit. The conductor is connected to one side of the lamp 25, the opposite side thereof being grounded in the usual manner. As an additional precautionary element, a whistle 29 is connected into the side of the cylinder 7, at such a height that 15 when the piston 8 is at its uppermost position, so that the arm 15 is thrown into its operative angle, the air admitted into the bottom of the cylinder may escape through the whistle 29 to audibly advise the traffic that a signal is being displayed.

20 In order to provide an air supply for the several signals, an air tank 37 is provided, together with a pump 38 which is suitably mounted upon or adjacent the automobile engine, a pipe 39 connecting the tank and the pump. The pump 38 is driven by means 25 of a belt 40 which passes over a pulley 41 upon the engine shaft and a pulley 42 upon the crank shaft 43 of the pump. The tank 37 is provided with a blow-off valve 44 which 30 is automatic in its operation to relieve the pressure within the tank when the predetermined maximum has been reached. The tank 37 is connected by means of a pipe 45 to a distributing valve 46. The distributing 35 valve 46 is mounted in a convenient position upon the dash-board or instrument board of the machine, and includes, in a single casting, suitable mechanism to operate the forward signals.

40 Thus, in accordance with the will of the driver, he may signal to following traffic a turn to the right or left, or intention to stop the machine. The apparatus is equally effective for day or night use, and of such a 45 simple and practical nature that it may be installed upon any automobile now in use, or may be inconspicuously embodied in the equipment of new machines. In this connection it should be noted that the working 50 parts of the forward signals may be completely housed by a casing 69, as shown in Figs. 10 and 11, the casing being secured

to the base plate 2, and having the slot 70 which will permit the movement of the arm 15 into horizontal position. 60

While the form which has been described is that which is now preferred, it is obvious that the invention may be embodied in various modified mechanisms without departing from the spirit of the invention or the 65 scope of the appended claims.

Having thus described the invention, what is claimed as new, is:—

1. A direction indicator for automobiles comprising a base plate, a cylinder on said 70 plate, a piston and stem movable in said cylinder, said stem extending upwardly through the top thereof and having an angular upper end, a slotted guide block secured on said base slidably receiving said angular 75 end of the piston stem, a link connected to said stem for transverse swinging movement, a semaphore arm pivotally mounted on said base, a disk at the lower pivoted end of said arm and pivotally connected to the 80 free end of said link, means for actuating said piston to move the arm to horizontal signaling position, means for limiting the movement of said arm into signaling position, and spring means connected to the said 85 stem and to the cylinder to return said arm to vertical non-signaling position upon the release of the first named means.

2. A direction indicator for automobiles comprising a base plate, a cylinder on said 90 plate, a piston and stem movable in said cylinder, said stem extending upwardly through the top thereof and having an angular upper end, a slotted guide block secured on said base slidably receiving said angular 95 end of the piston stem, a link connected to said stem for transverse swinging movement, a semaphore arm pivotally mounted on said base, a disk at the lower pivoted end of said arm and pivotally connected to the free end 100 of said link, means for actuating said piston to move the arm to horizontal signaling position, means for limiting the movement of said arm into signaling position, spring means connected to the stem and to the cylinder to return said arm to vertical non-signaling position, and means connected to said base to limit the movement of said arm to vertical non-signaling position. 105

In testimony whereof I affix my signature. 110
